United States Patent Office

Des. 222,453
Patented Oct. 26, 1971

222,453

ARMCHAIR

John W. Ziss, and Frank R. Ziss, both of 6413 E.
Sprague Road, Independence, Ohio 44131

Filed June 4, 1970, Ser. No. 23,311

Term of patent 14 years

Int. Cl. D6—02

U.S. Cl. D15—1

FIG. 1

FIG. 2

FIG. 3

FIG. 4

FIG. 5

FIG. 6

FIG. 1 is a three-quarter isometric view of the right side of a chair embodying our new design with a single cushion applied to the back and seat;

FIG. 2 is a left side elevation thereof with the cushion removed for convenience of illustration;

FIG. 3 is a front elevation of the FIG. 2 chair;

FIG. 4 is a rear elevation of the chair as shown in FIG. 2;

FIG. 5 is a top plan view of the chair as shown in FIG. 3; and

FIG. 6 is a bottom plan view of the chair as shown in FIG. 4.

We claim:

The ornamental design for an armchair, as shown and described.
